UNITED STATES PATENT OFFICE.

CHARLES M. BARKER, OF PLYMOUTH, WISCONSIN.

PORTRABLE SAWING-MACHINE.

No. 925,553.

Specification of Letters Patent.

Patented June 22, 1909.

Application filed February 6, 1909. Serial No. 476,352.

To all whom it may concern:

Be it known that I, CHARLES M. BARKER, a citizen of the United States, and resident of Plymouth, in the county of Sheboygan and State of Wisconsin, have invented certain new and useful Improvements in Portable Sawing-Machines; and I do hereby declare that the following is a full, clear, and exact description thereof.

10 The object of my invention is to provide a durable, simple and light portable motor-driven reciprocative saw, its construction and arrangement being such that it can be readily transported and operated in forests, 15 by a single operator, its various adjustments rendering it possible to effectually operate upon either standing or felled timber.

With the above objects in view, the invention consists in various details of construction and combination of parts as set forth hereinafter with reference to the accompanying drawings and subsequently claimed.

In the drawings: Figure 1 represents a side elevation of a portable reciprocative sawing-machine embodying the features of my invention, the machine being shown in the position assumed when sawing a horizontal log and with parts broken away and other parts in section to better illustrate the structural features; Fig. 2, a plan view of the same with parts broken away and in section; Fig. 3, a plan view of the forward portion of the machine with the working parts in the position they assume when sawing standing timber, detail parts of the machine being broken away and in section to more clearly illustrate the invention; Fig. 4, a fragmentary detail side elevation of the saw-adjusting and reciprocative guiding mechanism upon an increased scale, the view being taken looking toward the drive-side of the machine; Fig. 5, a cross-section of the machine, as indicated by line 5—5 of Fig. 2; Fig. 6, a cross-section of the same, as indicated by line 6—6 of Fig. 2; Fig. 7, a cross-section taken upon line 7—7 of Fig. 2; Fig. 8, an enlarged detail sectional plan view of the saw-driving-mechanism and a portion of the frame, the motor being removed therefrom; Fig. 9, an enlarged detail section view of the saw-tension device and cross-head, the view being taken upon line 9—9 of Fig. 3;

Fig. 10, an enlarged detail section on line 10—10 of Fig. 8, showing the clutch controlling lever lock, and Fig. 11, a detail cross-section of the machine, as indicated by line 11—11 of Fig. 1, the view illustrating one form of support for the saw end of the machine.

Referring by numerals to the drawings, 1, 2, indicate skeleton brackets that are suitably braced and connected by cross-rod 3 to constitute a motor-frame section, in which motor frame section is supported a motor 4 of any standard construction, the motor in this instance being shown as of the internal combustion type, for which an oil-supply tank 5 is provided and is suitably secured to said motor frame.

A motor-shaft 6 carries a sprocket-wheel 6^a that is in link-belt connection with a larger sprocket-wheel 6^b, which sprocket-wheel is carried by a hollow counter-shaft 7, the latter being mounted upon a fixed arbor 8 provided with ball-bearings for the hollow counter-shaft. The ends of the arbor 8 in turn are fitted into adjustable bearing-blocks 8^a supported by the motor-frame, by means of which adjustment the slack in the aforesaid link-belt is regulated together with the slack in a similar link-belt that is carried by a smaller sprocket-wheel 9 also fast on the counter-shaft 7, this last named link-belt being designed to impart motion to sprocket-wheel 10 loosely mounted upon a driving-shaft 11. The sprocket-wheel 10 carries one member of a friction-clutch 12, the opposite clutch-member 13 being in spline-connection with the driving-shaft. A hollow hub 14 of the clutch-member 13 has fitted therein a coil-spring 15 that is held under tension by an adjustable collar 16, which collar is in screw-threaded engagement with the driving-shaft end, as best shown in Fig. 8. Loosely fitted within an exterior annular groove of the hollow hub 14 is a ring 17 provided with studs for engagement with the spanner portion of a clutch-lever 18, the clutch-lever being fulcrumed to the motor-frame. The driving-shaft 11, like the counter-shaft, is provided with suitable ball-bearings as shown, which ball-bearings in this instance are carried by the motor-frame, there being a housing or sleeve fitted over

said drive-shaft between the skeleton brackets of said motor frame.

When the clutch-members are thrown into engagement, the clutch-lever is locked by 5 means of a dog 19, which dog is pivoted to the adjacent skeleton bracket 1 and is adapted to engage and hold said clutch-lever in its locked position, it being understood that the coil-spring is adjusted to exert sufficient 10 pressure between the clutch-members to cause rotation of the driving-shaft under a predetermined load condition. By utilizing a spring-controlled friction-clutch, as described, should the saw or other mechanism 15 become choked or stopped for any cause, said clutch will stop and thus prevent a breakdown or overstrain of the machine.

The motor frame, driving-gear and various 20 adjustments and clutch described, are designed with a view to obtaining the maximum of strength combined with a minimum of weight together with efficiency and economy in developing the required power, and it should be understood that these details may 25 be varied within the knowledge of skilled mechanics to accomplish the desired objects.

Secured to the driving-shaft opposite its clutch-end, is the hub of a crank-wheel 20, which crank-wheel comprises a pair of parallel disks that are fast to said hub and also 30 connected by bolts or rivets passing through thimbles interposed between the disks, this construction being preferable in order to insure rigidity and lightness, although if desired I may in some instances use a fly-wheel either in the form of additional weight to the 35 crank-wheel or a separate wheel, in which case the same could be attached to the clutch-end of the driving-shaft to effect a 40 more perfect balance in opposition to said crank-wheel.

The forward end of the motor frame comprises a head 20^a, which head is secured by bolts between the skeleton brackets 1, 2, respectively. Brazed or otherwise secured to 45 the head 20 are a series of longitudinal tubes 21, the tubes being all secured to an intermediate spider 22, while the main or backbone tube 23 of the series together with two of the 50 auxiliary tubes extend through said spider and are also connected to an outer head 24. The auxiliary tubes 21 terminate at the outer head 24, while the backbone tube 23 projects beyond the same to form inner and 55 outer bearings for a saw-table 25, the latter being provided with apertured ears 26, 27, that are loosely mounted upon said backbone tube. The outer ear 27 of the table is abutted against a collar fast on the tube 23, 60 and the inner ear abuts the adjacent face of the outer head 24 and is provided with a handle 28 having a spring-controlled dog 29 for engagement with notches of a detent 30 forming part of said outer head. From the 65 foregoing description it will be understood

that the saw-table can be swung to a vertical or horizontal position by means of the handle 28, in either of which positions it may be locked by the dog engaging the notches of the detent, whereby adjustment of the saw is 70 effected to cut in a vertical or horizontal position, the saw being supported and guided by said saw-table in a manner to be described.

The arrangement of tubes which extend 75 from the motor-frame and together therewith constitute a support for the saw-table, may be varied or brazed in any manner consistent with well known laws of such structural work, and it is obvious that in some instances, the motor-frame section may be 80 formed by continuing said tubes rearward and bending the same upon themselves to form the outer members of the skeleton brackets 2 in place of forming the latter in separate castings as shown. 85

Swiveled to an adjustable lug-extension 31 fast upon the skeleton bracket 2 is a hanger 32, which hanger carries a pair of parallel guide-rods 33 that are connected at their outer ends to a vertically disposed sector 34. The sector teeth are meshed with a worm 35 carried by an arbor mounted in bearings of a bracket 36, which bracket is secured to the intermediate spider 22 and is provided with guide-wings 37 that overlap 95 and engage the edges of the toothed sector to prevent lateral play of the same. The worm spindle is provided with a hand-wheel, by means of which said worm is rotated, whereby the elevation of the guide-rods in connection with the sector 34 is regulated, said guide-rods being swung upward or downward upon the rearward swivel-connection. A cross-head 38 is slidably mounted upon the guide-rods 33 and is provided with a stud 100 39 upon which is fitted one end of a pitman 40, the opposite end of the pitman being connected to a wrist-pin 41 carried by the crank-wheel 20, by means of which pitman reciprocative motion is imparted to the cross-head. 110 Directly forward of and aligned with the stud 39 is a centrally apertured ear 42 that projects from the cross-head, the axis of the aperture therein being at a right-angle to the axis of said stud 39. Fitted into the aperture of the ear 42 is the shank of a clip 43, which clip is provided with a spring-controlled plunger 44, that is adapted to engage either one of a pair of notches 45 formed in the face of said ear 42, the notches being 115 spaced apart at an approximate angle of ninety degrees. By the arrangement just described it will be seen that the clip may be adjusted from a vertical to a horizontal position and locked in either position for the 120 purpose of accommodating the saw when said saw is to be adjusted either for vertical or horizontal work, the saw being connected to said clip in a manner to be described hereinafter. A saw-carrying rod 46 is pivoted 125 130

between the ears 48 of the clip, the axis of the pivot-pin of which rod is alined with and forward of the shank of said clip but at a right-angle to said shank. The forward end of the 5 rod 46 is provided with a socket-plate in which is suitably secured a saw-blade 49, the latter being parallel with the saw-table 25 and is supported and guided therein by means of a shoe 50 carried by said saw-table, 10 the shoe having a flat spring tongue 51 that overlaps and exerts pressure upon the upper face of said saw-blade.

It will be readily understood from the foregoing description, that reciprocal motion is imparted to the saw-blade through its 15 connection with the crank-wheel, and in order to insure a positive feed of said saw-blade, whereby the teeth of the same are held to their work, I have provided a spring-power feed in connection with the saw together with provision for adjusting the 20 spring-power in order that feed may be relative to the condition required or material being cut. With this object in view an arm 25 52 having branches 53 that are connected by a sleeve 54 is pivoted between the ears of the clip 43, the sleeve being provided with an aperture through which a pivot pin 55 passes, which pin is carried by said clip-ears, as best 30 shown in Figs. 3, 4, and 9. One end of a coil-spring 56 engages a stud 57 that extends from one of the clip-ears 48, the spring being coiled about the sleeve 54 of the arm and terminates with a hooked end, which end 35 is socketed into a washer 59. This washer is loosely mounted upon the sleeve 54 and is provided with a series of radial spokes 60, which spokes are adapted to be engaged by a loop 61 that is slidably mounted upon the 40 adjacent bracket 53 of the arm 52, the said loop being held in adjusted position upon the branch, by a suitable set-screw. The outer end of the arm 52 terminates in an apertured head, through which head the saw-carrying 45 rod 46 passes, the spring-tension exerted by the arm 52 thereon being thus transferred to the saw-blade. Should it be desired to increase or decrease this tension, it is evident that the washer 59 may be turned either to 50 wind or unwind the coil-spring, said washer being thereafter locked by means of the slideable loop.

To control the saw in opposition to the spring-pressure exerted thereon, a lever 62 is 55 fulcrumed to the saw-table having its free end provided with a concaved roller, which roller engages the saw-carrying rod 46. The lever 62 is in link-connection with a hand-lever 63 that is also fulcrumed to the saw-table and provided with a spring-controlled 60 pawl for engagement with a notch in a detent forming part of said saw-table. By means of the hand-lever the saw-blade may be withdrawn from a saw-kerf and locked in the position as shown in Fig. 3, in which position the

saw-teeth are held beyond the line of the log to be cut preparatory to setting the machine in working-position, the saw-blade being thereafter released by the operator freeing the pawl of the hand-lever 63 from the 70 detent.

Log-chucking mechanism comprising a dog 64 is adjustably mounted upon a draw-bar 65, one end of which draw-bar is hinged to a hand-crank 66 fulcrumed to the saw-table. 75 The dog 64 is arranged to engage the log in opposition to a fixed dog 64^a carried by said saw-table, as shown in Fig. 1, and when the log is chucked the hinge-connection of the hand lever passes across a line drawn 80 through the fulcrum-point of said hand-lever a sufficient distance to constitute a lock, the aforesaid hand-lever being stopped by a pin 66^a that projects from the saw-table. For the purpose of an additional support for the 85 saw-end of the machine in connection with the chucking-mechanism, when said machine is operating upon standing timber, I have provided a spur 67 located intermediate of the described chucking dogs. The spur is 90 also carried by the saw-table and is inclined at an angle thereto in a downward direction, whereby the weight of the front end of the machine will cause the spur to enter the log and thus assist in supporting said weight. 95

As shown in Figs. 1 and 11 of the drawings, the motor-frame section is provided with a brace-bar 68 having a horizontally disposed pintle, upon which pintle is hung a supporting truck 69, the latter being provided with 100 runners 70 for convenience in supporting and transporting the machine. For these runners however, in some instances, wheels may be substituted contingent upon climatic conditions. The pintle-connection between the 105 motor-frame section and truck permits the machine to assume a level working position without regard to the nature of the ground upon which the truck is resting, the opposite end of said frame being supported by the 110 chucking-mechanism and saw-table in connection with a log to which said machine is attached.

As illustrated in Figs. 1 and 2 of the drawings, the machine is set to operate upon a 115 horizontal log and the chucking-mechanism is locked together with the saw controlling lever 62. In starting the machine, the controlling lever 62 is first released to permit the coil-spring 56 through its connection to act, 120 thus causing the saw-blade teeth to be pressed against the log with the necessary cutting-force. The motor being now started, reciprocal motion is imparted to the saw-blade, whereby it performs the usual 125 cutting, entering at each stroke deeper into the log. When operating upon horizontal logs, as shown in Figs. 1 and 2, should the same be of great diameter, it is obvious that the saw-carrying rod 46 will change its angle 130

with relation to the line of travel of the cross-head as the saw-blade descends into the log and consequently the power exerted by the pitman would have more or less tendency to cause a buckling effect upon the said rod. This tendency is overcome by means of the swiveled guide-rods 33 being adjusted as to angle from time to time relative to the saw-carrying rod by means of the worm and toothed sector before mentioned. After the saw-blade has entered the kerf a sufficient distance, it leaves the guide-shoe 50 and tongue 15, the latter parts being only necessary at the start in the operation. To set the machine from its position for operating horizontal logs to a position for operating upon standing timber, the spring controlled plunger 44 of the cross-head clip together with handle 28 of the saw-table 25 are released. The saw-table is then revolved upon the back-bone tube 23, by means of the handle 28, to a horizontal position as shown in Fig. 3, in which position it is locked by the pawl and detent, the clip 43 being also turned upon its shank until the plunger 44 locks into the upper notch of the clip-ear 42 corresponding to the position of said clip. Thus it will be seen that the saw-blade has been reversed from a vertical cutting position to a horizontal cutting position together with the axis of both the saw-carrying rod 46 and arm 52, whereby the spring-pressure of the latter is directed to exert its force in the line of cut.

Having thus described mechanism for carrying out my invention, it is apparent that a machine of the type described may be constructed economically and light and so conveniently arranged as to render it capable of being transported and manipulated by a single operator, in any location where it is possible for the operator to have access thereto, it being desirable as far as the structural features are concerned, to employ standard parts accessible in the open market. The adjustable lug-extension 31, as best seen in Fig. 4, is designed to be raised or lowered, whereby the rear ends of guide-rods 33 may be set at different angles relative to the frame for the purpose of changing the angle of said guide-rods at this end in addition to the adjustment previously described in connection with the forward ends thereof.

I claim:

1. A portable reciprocative sawing-machine comprising a skeleton-frame, a motor carried by the frame at one end thereof, a crank-wheel revolvably mounted in the frame adjacent to the motor and in gear-connection therewith, an angularly adjustable saw-table carried by the skeleton-frame opposite its motor end, a saw-blade in sliding engagement with the saw-table, log-chucking means carried by said saw-table, a cross-head, guides for the cross-head carried by the frame, a spring-controlled rod connected to

the saw-blade, the rod being journaled on said cross-head, means for effecting adjustment of the pivotal connection between the rod and cross-head, and a pitman-connection between the aforesaid cross-head and crank-wheel. 70

2. A portable reciprocative sawing-machine comprising a motor frame section, having a series of longitudinal forwardly extending tubes, a head in rigid connection with the tube-ends, a saw-table supported by the tubes having angular adjustment relative to the head, a saw-blade in sliding engagement with the saw-table, a motor-driven reciprocative cross-head supported by the longitudinal tubes, an adjustable spring-controlled rod connected to the cross-head, and to the saw-blade. 75 80

3. A portable reciprocative sawing-machine comprising a motor frame section having a series of longitudinal forwardly extending tubes, a head secured to the tube-ends, a saw-table supported by the tubes, having angular adjustment relative to the securing head, a saw-blade in sliding engagement with the saw-table, a motor-driven reciprocative cross-head supported by the longitudinal tubes, an adjustable spring-controlled rod connected to the cross-head, and to the saw-blade, a hand-lever in connection with the spring-controlled rod, and log-chucking mechanism in connection with the saw-table. 85 95

4. A portable reciprocative sawing-machine comprising a motor-frame section having a series of longitudinal forwardly extending tubes, a head secured to the tube ends, a saw-table supported by the tubes, having sliding adjustment relative to the head, a saw-blade in connection with the saw-table, a motor-driven reciprocative cross-head supported by the longitudinal tubes, an adjustable spring-controlled rod connected to the cross-head, and to the saw-blade, a supporting-truck in connection with the motor-frame section, and log-chucking mechanism 100 105 110 in connection with the saw-table.

5. A portable reciprocative sawing-machine comprising a skeleton-frame, a motor carried by the frame at one end thereof, a drive-shaft, a spring-controlled friction-clutch mechanism carried by the drive-shaft, a counter-shaft in gear-connection with the motor and one member of the friction-clutch mechanism, an angularly adjustable saw-table connected to that end of the skeleton-frame opposite the motor end, log-chucking mechanism carried by the saw-table, a saw-blade located adjacent to and parallel with the saw-table, a guide-shoe for the saw-blade carried by said saw-table, parallel guide-rods 115 120 125 130 135 adjustably supported by the skeleton-frame, a reciprocative cross-head carried by the guide-rod, a spring-controlled rod connected to the cross-head at one end, and secured at its opposite end to the saw-blade, a control-

ling-lever for the rod, a hand-lever in link-connection with the controlling - lever, a crank-wheel secured to the drive-shaft, and a pitman in connection with the crank-wheel 5 and cross-head.

In testimony that I claim the foregoing I have hereunto set my hand at Plymouth, in

the county of Sheboygan and State of Wisconsin in the presence of two witnesses.

CHARLES M. BARKER.
